UNITED STATES PATENT OFFICE.

JOHN D. ROBNETT, OF CHICAGO, ILLINOIS.

HORSESHOE.

1,111,861.

Specification of Letters Patent. Patented Sept. 29, 1914.

Application filed February 28, 1912. Serial No. 630,439.

To all whom it may concern:

Be it known that I, JOHN D. ROBNETT, a citizen of the United States, residing at Chicago, in the county of Cook and State 5 of Illinois, have invented a certain new and useful Improvement in Horseshoes, of which the following is a specification.

This invention relates to horseshoes, and has for its object to provide a new and improved device of this description.

The invention is illustrated in the accompanying drawings, wherein—

Figure 1 is a bottom view of a horseshoe embodying the invention. Fig. 2 is a top view of one of the ends or heels of the shoe. Fig. 3 is a sectional view taken on line 3—3 of Fig. 1. Fig. 4 is a sectional view taken on line 4—4 of Fig. 1. Fig. 5 is a bottom view of one of the heels of the shoe 20 with the cushion removed.

Like numerals refer to like parts throughout the several figures.

The shoe is provided with a main or body portion 1, having the inner edge 2 made thinner than the main portion so as to lighten the shoe. The body portion is provided with holes 3 for the nails by means of which the shoe is fastened to the horse's foot. Each heel of the shoe is provided 30 with a cushion receiving receptacle integral therewith and having the side walls 4, and the front walls 5 and the bottom pieces 6, said receptacles being open at their inner or opposed sides as shown. The bottoms of 35 the receptacles have portions 7 which project inwardly beyond the outline of the shoe, a portion of each wall 5 projecting beyond such outline. The bottom pieces 6 are provided with openings 8 through which the 40 cushioning material passes into the recess 9 at the top of the shoe. I prefer to use rubber as a cushioning device, and in this event, the rubber is applied while hot passing through the openings 8 so as to fill the recesses 9. The recesses 9 when the shoe is 45

on the horse are located below the horse's heels so that the rubber or other cushion portion 10 comes into contact with the horse's heel and prevents the horse from 50 having corns. The cushions 11 in the receptacles of the heels of the shoe engage the ground so as to form a heel cushion for the horse. It will be noted that the bottom piece 6 is substantially in the same plane as 55 the main portion or body of the shoe. The rubber is vulcanized to the shoe and is addi-

tionally held in place by the part 10. The portions 7 of the bottom pieces of the cushion receptacles preferably have their upper faces below the upper faces 12 of the 60 shoe (see Fig. 3). These portions 7 are provided with holes 13 which are preferably inclined or beveled as shown in Fig. 3 and into which the cushioning material passes, the beveled effect acting to hold the cushioning 65 material in place. The shoe is provided at the front with a toe culk 14.

The use and operation of my invention are as follows: The shoe is made up and the cushions 11 placed in the cushion 70 receptacles. The shoe is then nailed to the horse's foot by means of nails through the holes 3. When in place, the heel cushions take up the jar and are easy on the horse's feet. They also prevent the formation of 75 corns. It will further be noted that the heels of the shoes only come in contact with the heels of the horse, the frogs of the horse's feet being entirely free therefrom. This is true regardless of the size of portion 80 7 as said portions are below the upper face of the shoe and hence do not make pressure contact with the horse's feet. As the shoe wears, the cushions wear away and the edges of the cushion receptacles also 85 wear away. Since the bottom portions 6 of the receptacles are in the plane of the body portion of the shoe, it will be seen that substantially all of the rubber or other pad 90 may be used. This is a very important feature as it makes an economical shoe and increases the life of the shoe and its efficiency. The receptacles being integral with the shoe are fixed in position and may be made comparatively light. This arrangement permits the construction whereby substantially 95 all of the pad may be used before the shoe is discarded. This construction is very beneficial for horses having bad tendons as it relieves the jar as the foot comes into contact with the ground.

I claim:

1. A horseshoe comprising a body portion, cushion receptacles at the heels thereof integral with the body portion, said cushion 105 receptacles provided with bottom pieces, said bottom pieces provided on the side thereof opposite to that on which the cushion receptacles are located, with recesses having upstanding walls extending completely 110 there around said bottom pieces substantially in the same plane as the body por-

tion of the shoe, projecting walls for the front and outer sides of said cushion receptacle, the inner opposed sides of said cushion receptacle being open, and independent separated cushions in said cushion receptacles.

5. A horseshoe comprising a body portion, cushion receptacles at the heels thereof integral with the body portion, said cushion receptacles provided with bottom pieces substantially in the same plane as the body portion of the shoe, said bottom pieces projecting laterally toward each other beyond the outline of the shoe and out of contact with each other, a recess associated with 10 said bottom pieces on the side thereof opposite to the side where the cushions are located, an upstanding wall extending entirely around each of said recesses, a portion of said bottom pieces projecting beyond 15 said recesses.

3. A horseshoe comprising a body portion, cushion receptacles at the heels thereof integral with the body portion, said cushion receptacles provided with bottom pieces substantially in the same plane as the body portion of the shoe, recesses at the heels of the shoe above said bottom pieces and on the side of the shoe opposite the cushions each recess provided with outstanding walls and 25 entirely surrounding it, a portion of the bottom piece extending beyond the recess and cushioning material in said cushion receptacles and said recesses, the cushioning material in the recesses adapted to come in 30 contact with the horse's hoof.

4. A horseshoe comprising a body portion, cushion receiving receptacles integral with the heels thereof, bottom parts for said

cushion receiving receptacles, said bottom parts provided with portions which project 40 inwardly beyond the outline of the shoe, the upper face of said portions being below the upper face of the shoe.

5. A horseshoe comprising a body portion, cushion receiving receptacles integral 45 with the heels thereof, bottom parts for said cushion receiving receptacles, said bottom parts provided with portions which project inwardly beyond the outline of the shoe, the upper face of said portions being below 50 the upper face of the shoe, an opening extending through each of said projecting portions having an inclined face, cushions in said cushion receiving receptacles and provided with portions which project through 55 said openings.

6. A horseshoe comprising a body portion, cushion receptacles at the heels thereof integral with the body portion, said cushion receptacles provided with 60 pieces substantially in the same plane as the body portion of the shoe, an upstanding wall extending lengthwise of the shoe between the sides of each of said bottom pieces, the body portion of the shoe between the cushion receiving receptacles and the toe being flat and provided with nail holes, the inner side of said body portion 65 being reduced in thickness.

Signed at Chicago, Illinois, this 23rd day 70 of February, 1912.

JOHN D. ROBNETT.
